Thomas B. Hope
Inventor:

UNITED STATES PATENT OFFICE.

THOMAS B. HOPE, OF CHICAGO, ILLINOIS.

ENVELOPED COMBINATION RECORD, INVOICE, RECEIPT, AND SHIPPING TAG.

1,264,798.

Specification of Letters Patent. Patented Apr. 30, 1918.

Application filed April 19, 1915. Serial No. 22,526.

To all whom it may concern:

Be it known that I, THOMAS B. HOPE, a citizen of the United States, residing at Chicago, in the county of Cook and State 5 of Illinois, have invented a certain new and useful Improvement in Enveloped Combination Record, Invoice, Receipt, and Shipping Tags, and declare the following to be a full, clear, and exact description of the 10 same, such as will enable others skilled in the art to which it pertains to make and use the same, reference being had to the accompanying drawing, which forms a part of this specification.

15 The object of my invention is to produce a simple and novel device which may be employed as a tag but shall be capable of carrying memoranda, records, receipts, invoices, as well as shipping directions or 20 other notations for which tags are usually employed and protect such records, etc., against weather and against injury or effacement through contact with exterior objects and against grease and dirt on the 25 hands of those through whom the tag passes.

The various features of novelty whereby 30 my invention is characterized will herein-after be pointed out with particularity in the claims; but, for a full understanding of my invention and of its objects and advantages, reference may be had to the following detailed description taken in connection with the accompanying drawing, 35 wherein:

Figure 1 is a perspective view of a device arranged in accordance with a preferred form of my invention, in an unfolded or open condition; and

40 Fig. 2 is a longitudinal central section through the device in its folded or closed condition.

Referring to the drawing, 1 represents the body section of my device which may 45 be of any size and shape the tags of various kinds now have or of any size and shape that may be required by the work the device is to do. Attached to one end of the member 1 is a member, 2, substantially as long as the member 1 and preferably of the same size and shape. Attached

to the other end of the member 1 is a member, 3, which is preferably made of about the same width as the member 1 but quite short in length. The members 1, 2 and 3 55 may be made of any suitable material though ordinarily they will be made of a single strip of heavy, tough paper such as is employed in the manufacture of tags; the member 1 constituting the body section, the 60 member 2 the flap section and the member 3 the clamping section. The member 3 is folded back upon the member 1 and is held in this position by an eyelet, 4, passing through the same and through the underlying body section. The eyelet is preferably placed at an appreciable distance from the fold between the sections 1 and 3, a sufficient space between the eyelet and the fold being ordinarily obtained by placing the 70 eyelet at about the center of the clamp section. Extending inwardly from the edge of the flap section 2 at the end opposite the end which is joined to the body section 1, is a notch, 5, which is so located relatively 75 to the side edges of the flap as to permit it to register with the eyelet when the free end of the flap is inserted underneath the clamping section and the length of the notch being such that the end of the flap section may 80 abut against the fold between the sections 1 and 3. Furthermore, the notch is preferably made wider than the diameter of the eyelet so that the material of which the clamping section is made will be given an 85 opportunity in the vicinity of the eyelet to bend outwardly when the end of the flap section is introduced, in case the eyelet be driven so tightly as to press the center of the flap section tightly against the body section. 90

Both sides of the sections 1 and 2 may be employed to carry data, if desired, but, whatever is carried on the two inner faces or sides is effectually concealed and shielded when the free end of the flap section is inserted under the clamp section. The device may be attached to an object of any kind by a cord, 6, or other device passing through the eyelet which thus serves not only 95 as a fastening device for the clamp section but also as a receiver for the tag attach- 100

ing device. Furthermore, the eyelet serves as a centering device for the free end of the flap section and prevents lateral movement thereof. This, with the steady and locking effect of the engagement of the free edge of the flap section with the bend or fold between the body section and clamp section makes the device windproof so that there will be no danger that the flap section 10 will become loose or partly loose when exposed in windy weather.

In some cases it will be found advantageous to perforate the flap section near the free end, to make it easy to file the flap 15 section when it is severed from the body of the tag. In the arrangement illustrated, there are two perforations, 7 and 8, one on each side of the notch 5.

As a shipping tag and informal invoice, 20 C. O. D., or receipt for delivery, the enveloped section of the tag affords ample room for memoranda such as—date of order—order number—quantity ordered—quantity shipped—amount to follow—size—etc., all 25 of which, and sometimes more, is actually demanded by modern business methods; the same being now taken care of by involved systems including separate and distinct forms of stationery in addition to a shipping 30 tag proper and much clerical work. The greatest value of the device is, however, expected to develop in factory, shop and storage, where tags containing important data and valuable records, in many cases the only 35 means of identification, are indispensable and which, because of the careless rough handling and exposure to which they are subjected are usually damaged or utterly destroyed before they have performed half the 40 services expected of them.

Another use to which my invention may be put is that of a mailing card, circular or other device which will go through the mails.

45 While I have illustrated and described with particularity only a single preferred form of my invention and recited a few uses thereof, I do not desire to be limited to the exact structural details thus illustrated and 50 described and to uses recited; but intend to cover all forms and arrangements which come within the terms employed in the definitions of my invention constituting the appended claims and all uses to which said invention may be put.

I claim:

1. A tag comprising a body section, a flap section connected to the body section at one end of the latter, a clamp section attached to 60 the opposite end of the body section, the body section and the flap section being of substantially the same length and the clamp section being quite short, the clamp section being folded back on the body section, an

eyelet passing through the clamp section and 65 the body section, and the free end of the flap section having a notch extending inwardly from the edge thereof far enough to permit the latter to be brought into proximity to the fold between the clamp section and the 70 body section when the free end of the flap section is inserted beneath the clamp section.

2. A tag comprising a body section, a flap section connected to the body section at one end of the latter, a clamp section attached 75 to the opposite end of the body section, the clamp section being folded back on the body section, an eyelet passing through the clamp section and the body section at some distance from the fold between the same, and the 80 free end of the flap section having a notch extending inwardly from the edge thereof in position to register with the eyelet when the free end of the flap section is inserted beneath the clamp section, said notch being 85 longer than the diameter of the eyelet.

3. A tag comprising a body section, a flap section connected to the body section at one end of the latter, a clamp section attached to the opposite end of the body section, the 90 body section and the flap section being of substantially the same size and shape and the clamp section being quite short, the clamp section being folded back on the body section, an eyelet passing through the body sec- 95 tion and the clamp section at about the middle of the latter so as to lie at some distance from the fold, the free end of the flap section having a notch extending inwardly from the edge thereof in position to receive the eyelet 100 when the free end of the flap section is inserted under the clamp section.

4. A tag comprising a body section, a flap section connected to the body section at one end of the latter, a clamp section attached 105 to the opposite end of the body section, the body section and the flap section being of substantially the same size and shape and the clamp section being quite short, the clamp section being folded back on the body 110 section, an eyelet passing through the body section and the clamp section at about the middle of the latter so as to lie at some distance from the fold, the free end of the flap section having a notch extending in- 115 wardly from the edge thereof in position to receive the eyelet when the free end of the flap section is inserted under the clamp section, said notch being longer and also wider than the diameter of the eyelet.

5. A device of the character described comprising a body section, a flap section, and a clamp section made of a single strip of material adapted to be folded; a fastening device extending through the clamp section and the body section to produce a jaw open toward the flap section; and the flap section having a notch in its end to permit 125

the end of the flap section to straddle said fastening device when the free end of the flap section is inserted in said jaw.

6. A device of the character described comprising a body section, a flap section, and a clamp section made of a single strip of material adapted to be folded; a fastening device extending through the clamp section

and the body section to produce a jaw open toward the flap section; the flap section being long enough to engage with the fold between the other two sections when its free end is inserted in said jaw; and said flap section having in its free end a notch adapting it to clear said fastening device. 10

THOMAS B. HOPE.
